DANIEL FITZGERALD, OF NEW YORK, N. Y.

Letters Patent No. 91,732, dated June 22, 1869.

IMPROVED SIGNAL AND SWITCH FOR RAILWAYS.

The Schedule referred to in these Letters Patent and making part of the same.

To all whom it may concern:

Be it known that I, DANIEL FITZGERALD, of New York, in the county of New York, and State of New York, have invented certain new and useful Improvements in Railroad-Signals and Switches; and do hereby declare that the following is a full, clear, and exact description thereof, reference being had to the accompanying drawings, and to the letters of reference marked thereon.

The nature of my invention consists in the construction and arrangement of certain devices herein-after to be described, whereby signals can be transmitted from a train of cars, whether standing still or in motion, to the station, or to another train of cars, or *vice versa*; and also in the arrangement of certain devices whereby a switch, if placed wrong, will be changed by the approaching train itself.

In order to enable others skilled in the art to which my invention appertains, to make and use the same, I will now proceed to describe its construction and operation, referring to the annexed drawings, which form a part of this specification, and in which—

Figure 1 is a plan view;

Figure 2 is a side elevation; and

Figure 3 is a transverse vertical section.

A A represent the rails of the main track, and B B are the switch-rails, which are connected by a bar, C, having an arm, D, with a weight, E, attached underneath the track, so as to keep, by its own weight, the main track open at all times, unless acted upon by two hinged levers, F F, which are operated by another lever, G, pivoted to a standard at the side of the track.

By raising the lever G, the switch will be opened, and as soon as the force is removed from the same, then the weight E will at once bring the switch back, so that the main track is open.

Along the whole track are stretched telegraph-wires a a, and at regular intervals, said wires are brought across the track, as seen in Figure 1.

All these wires connect with some telegraph-apparatus at each station.

H represents a railroad-car, having, at a suitable point inside, a telegraph-apparatus, connecting with adjustable conductors b b, on top of the car.

These conductors are so arranged on top of the car that they will come in contact with the wires stretched across the track, or may be turned so as to come in contact with the wires alongside the track.

In either case, the electric current becomes momentarily established, and, consequently, notice is given at the station of the approaching train.

If the wires are stretched across the track at regular intervals, say, for instance, every mile or two, then, of course, the exact whereabouts of the train is also readily ascertained.

When the conductors b b are placed so as to come in contact with the wires stretched alongside of track, then the electric current becomes continuous, so that messages may be sent from the train to the station, or *vice versa*, or to and from another train.

It will readily be seen, that by these means, collisions or accidents of almost any kind may be avoided.

When the conductors b b are turned, so as to come in contact with the wires alongside the track, I may provide said conductors with friction-rollers, as shown in the drawings.

Should, by some means, the mechanism above described for operating the switch become out of order, and, consequently, the switch be open, then the train itself can be made to close the same in the following manner:

On one side of the main track is pivoted a bar, I, which extends over, and is pivoted to the bar C.

At the side of the outer or loose end of the bar I is placed an electro-magnet, J, from which wires c c extend, and connect with the wires a a, alongside of the track.

If the switch is closed, the bar I lies close up to the electro-magnet J; but if it is open, or partially open, then this end of the bar I is more or less distant from the magnet.

When the train now approaches the switch, and it is found to be open, the conductors b b are thrown outward, so as to come in contact with the wires a a, when the electric current at once causes the magnet to draw the bar I towards it, and, consequently, close the switch.

So as to notify the engineer of the approaching train that the switch is open, I provide a hollow post, K, a suitable distance from the switch, but close to the track, said post having an opening on the front side.

In the hollow post K is placed a plunger, d, attached to a cord, E, which cord passes over a pulley at the post, and extends towards another hollow post, L, placed near the switch, this end of the cord E being attached to a weight, N, in the hollow post L.

When the switch is open, this weight rests on the bar I, the post L being cut out sufficiently to allow the said bar to enter the post for that purpose, when the plunger d will be below the aperture in the post K.

But when the switch is closed, then the weight falls down, so as to bring the plunger d opposite the opening, and, being painted in some bright color, it will, even at a considerable distance, show that the switch is all right.

It will be observed that when the switch is closed, it cannot be opened without first raising the weight, and, consequently, at once change the signal in the post K.

For foggy weather, or when signals could not be seen, I attach to the switch an alarm, M, which is so constructed, that when the switch is open, the alarm is constantly sounding, but not when the switch is closed.

This alarm is connected with the bar C, so that the movement of said bar will operate the same.

Having thus fully described my invention, What I claim as new, and desire to secure by Letters Patent, is—

1. In combination with telegraph-wires and conductors, arranged as above described, an electromagnet to close a switch by an electric current, communicated to said magnet from an approaching train, substantially as herein set forth.

2. The arrangement of the switch-rails B B, bar C, arm D, weight E, and levers F F and G, all substantially as and for the purposes herein set forth.

3. The arrangement of the hollow posts K and L,

plunger d, connecting-cord e, and weight N, constructed and combined with a switch, as described, so as to signal to an approaching train whether the switch is open or not, all substantially as herein set forth.

4. In combination with the switch-rails B B, bar C, arm D, weight E, and levers F F and G, the alarm M, so constructed and connected with the bar C, that it will be sounded or set in motion when the switch is misplaced, substantially as herein set forth.

5. The arrangement of the telegraph-wires a a and adjustable conductors b b, provided with friction-rollers, all substantially as and for the purposes herein set forth.

DANIEL FITZGERALD.
